(57) **CLAIM**

The ornamental design for an identity verification terminal device, as shown and described.

DESCRIPTION

FIG. 1 is a perspective view 1 of an identity verification terminal device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view; and,

FIG. 8 is a perspective view 2 thereof.

The broken lines in the drawings are for the purpose of illustrating unclaimed portions of the identity verification terminal device and form no part of the claimed design.

1 Claim, 8 Drawing Sheets(56)
